UNITED STATES PATENT OFFICE.

BURT A. SLATER AND MICHAEL J. McDERMOTT, OF BOISE, IDAHO.

SIGNAL SYSTEM.

No. 902,118.

Specification of Letters Patent.

Patented Oct. 27, 1908.

Application filed March 5, 1908. Serial No. 419,361.

To all whom it may concern:

Be it known that we, BURT A. SLATER and MICHAEL J. McDERMOTT, citizens of the United States, residing at Boise, in the county of Ada and State of Idaho, have invented certain new and useful Improvements in Signal Systems; and we do declare the following to be a full, clear, and exact description of the invention, such as will enable others skilled in the art to which it appertains to make and use the same.

Our invention relates to signaling systems and more especially to a system adapted for use in connection with railways.

15 The object of the invention is to prevent head-on or rear-end collisions by signaling the engineers from the stations which they have passed.

Another object of the invention is to 20 notify the engineer of the fact that the station agent at the station which he has passed is not at his post of duty, therefore, making it dangerous to proceed without understanding that the track is first clear.

25 A further object is to enable the station agent to recall any train which has passed his station, and is still within his jurisdiction, by signaling the engineer in the cab of the engine.

30 Further objects of the invention will appear as the specification is read in connection with the accompanying drawings, in which

Figure 1 is a diagrammatic view of the system used; Fig. 2 is a diagrammatic view of 35 the cab circuit; Fig. 3 is an enlarged side elevation view of the signaling mechanism; and Fig. 4 is an enlarged side elevation view of the switch at the station. Fig. 5 is a detail side elevation of the rail switch, and Fig. 6 is

40 a top plan view thereof.

Referring more especially to the drawings, 1 and 2, represent the respective rails upon which the vehicles are adapted to run. Connected to the rail 1 and leading off 45 therefrom is a feed conductor, 3, which is connected to the battery, B', of the switch, A', and to a contact, 4, by means of a jumper wire, 5. Another wire, 6, is connected to the rail, 1, at one end and to a binding post, 7, on 50 the switch, A', and from thence through an electro-magnet, E, and to the binding post, 8, and thence to the battery, B², by the wire, 9.

The opposite pole of the battery, B², is 55 connected to a wire, 10, connected at one end with one of the line wires L', and at its oppo-

site end to a rail switch, B⁵, to be hereinafter described.

The electro-magnet, E, is provided with an armature, E', which normally holds a swinging lever, 11, out of engagement with 60 the contact, 4. This lever is pivoted upon the base of the switch and is pulled downward under the tension of a spring, 12, and is electrically connected to the binding post, 13, by a jumper wire, 14. The binding post 13 65 is connected to the line wire, L''.

As both stations are similar, we shall refer to them as station A' and A², and we shall, therefore, only describe the switch at station A' and the connections of the line wire at station A², with the switch apparatus. The line wire, L', leads to and is connected with the battery B³ and also to the rail switch, B⁶.

The battery, B³, is connected in a like manner to the electro-magnet, E', as is the 75 battery B², with the electro-magnet, E, and the wire, 15, which leads from the opposite binding post, is connected to the rail, 1. The line wire, L'', is connected to the binding post, 16, by a wire, 17, in a similar manner, as at station A', and is then run through the switch to the battery B⁴ and to the rail, 1, by a wire, 18. Leading off from the line wire L'' is a plurality of lead wires, 19, all connected to contact strips, or blocks, C, 80 which are arranged intermediate the rails, 1 and 2, at approximately 150 or 200 yards apart, as is found most expedient in practice.

85 Mounted upon the cab at any suitable point, such as the pilot, we provide a contact 90 brush, 20, which is connected by a copper wire, 21, to a binding post, 22, upon the signal box, 23. This binding post has leading from it a wire, 24, which is connected to an electro-magnet, M, controlling an armature, 95 25, pivoted upon a standard, 26, within a box and firmly held in raised position by a spiral spring, 27, which is attached to the armature at the rear of its pivotal point and to the bottom of the casing. The opposite end of 100 the circuit of the electro-magnet, M, is composed of a conductor, 28, which leads to the binding post, 29, and from thence to a metal part of the engine, preferably the axle, so as to electrically communicate with the rails. When the electro-magnet, M, is energized as 105 will be hereinafter described, the armature, 25, is attracted so as to release from its hook end, 30, the contact lever, 31, pivoted to the top of the casing, and connected in series by 110

a wire, 32, with the batteries, B⁷. The opposite lines of the batteries, B⁷, lead to a pivot block, 33, by means of a wire, 34. To this pivot block is connected the armature, 5 35, of the electro-magnet, E⁴, the winding thereof being connected to the contact piece, 36, by a wire, 37. The contact lever, 31, is actuated when released by a spiral spring, 38, to contact with a standard, 39, connected to 10 the electro-magnet, E⁴, by a wire, 40. It will be seen therefore that when the armature, 25, is attracted, the lever, 31, is released and completes a local ringing circuit in the cab of the engine over the following 15 path: battery B⁷, 32, 31, 39, 40, E⁴, 37, 36, 35, 34, back to battery. As the armature vibrates, it breaks contact with the contact piece, 36, and is returned to normal in the ordinary manner by the spring, 31. As long as 20 the contact lever is in engagement with the standard, 39, the armature will continue to vibrate and ring the bell, B⁸.

Before completing the circuit and describing the operation of the system, we shall refer in a cursory manner to the switch used in connection with the rails. This switch comprises a lever, 42, pivoted at one end to a metallic block, 43, which is secured to the rail with good electrical connection. The 25 opposite end of the lever is formed with a cam surface, 44, which projects above the rail, 1, and is held in such position by a spiral spring, 45, which is sufficient to resist the pressure of a hand car, but insufficient to resist the weight of passenger or other cars. Adjacent the forward end of the lever we secure to the rail a block, 46, of wood or other suitable insulating material, and mounted thereon a contact, 47, which is adapted to be 30 engaged by a flexible spring contact, 48, rigidly carried on the underside of the lever and having electrical connection with the pivot bolt thereof by a wire, 49.

The contact blocks, 47, of the switches at 35 the stations A' and A², are connected with the wires, 10, so that upon depression of the switch lever, the circuit of the relays, E, E² are completed.

At each station we have shown a bell 40 adapted to be operated by the armature, E', but it will be understood that any other form of signal may be used; which will notify the station master that a train has passed and that the switch mechanism should be restored to prevent delay to the train, unless 45 some instructions or conditions prevent its proceeding.

Having described the mechanical and electrical connections, we will now proceed with 50 the operation by tracing the circuits. A train approaching or passing the stations in the direction of the arrow marked "X" will operate the switch and bring the contact, 48, into engagement with the block, 47, and 55 thus complete a circuit from the plus pole of

battery B² to the rail, the wire 6, contact piece, 7, relay, E, binding post, 8, back to battery over the jumper wire, 9. This causes the magnetization of relay E and consequent attraction of its armature, E', and 60 the release of the lever, 11. The bell is rung at the station A', and a circuit completed from the battery B' over the plus side, over the jumper wire, 5, lever, 11, jumper wire, 14, binding post, 13, line wire, L' and to 65 the contact strips. Should the track be clear through and the station master at station A' have no communication to impart to the engineer, he would immediately restore the lever, 11, to its original position, and 70 thus disconnecting the partially completed circuit just described to the contact strips, C. If, however, there is danger ahead on the line, or the station master wishes to recall a train for any purpose whatever, he leaves 75 the lever in engagement with the contact, 6, thus completing the circuit to the strip, C. If, now the engine passes over the strip, a current flows from battery B' to the contact strip as C, as before described, and from 80 thence through the brush, 20, to the binding post, 22, wire, 24, relay, M, wire 28, binding post 29, and to the wheels of the cab, which bear upon the rails, 1 and 2. This completes the circuit of the relay, M, and its armature, 25, is therefore attracted to release 85 the contact lever, 31. When this is released the spring, 38, pulls it into engagement with the standard, 39, and completes the local circuit of the ringer, E⁴. The engineer will 90 thus be notified that the train must return to station A' for instructions. At the same time the switch, B⁵, is closed, a momentary current or pulse is sent over the wire L' from the battery, B³, through the switch, B⁵, to the 95 rail, 1, and over the wire, 15, to the relay, E². This relay is energized and attracts its armature which lets go the lever of the switch and allows it to contact with the contact, 4. The 100 circuit is completed over the jumper wire, 9, to the battery, B³. The bell is then rung at station A², and the circuit of battery, B⁴; to the contact switch, C, is thus completed.

From the foregoing it will be seen that no 105 train can pass either one of the stations without notifying the other stations that it has passed, and, if so desired, the station master at either station can notify a train going in either direction that the track is not clear, or that something out of the ordinary schedule 110 is being run on the tracks. The engineer has no way of ascertaining which station is calling, or in which direction the danger lies, but this may be attended to by simply placing 115 telephone sets at the stations and upon the cabs of the engines which could be connected with the rails or with the line wires so that when the engineer was signaled, he would put his telephone set in communication 120 with the station and ascertain the diffi- 125 13

culty. It is not thought necessary to illustrate such a construction, as such devices are well known in the art.

Having thus fully described our invention, what we claim as new and desire to secure by Letters Patent, is:

1. In a signaling system, electrically connected stations, track rails, vehicles traveling there-over, a source of current included in a circuit with a relay, said circuit being controlled by the vehicle traveling over the track rails, a second circuit including a source of current, means to partially complete said secondary circuit, signals operated at both stations upon completion of said first circuit, means carried by the vehicle for completing said second circuit, a local circuit controlled by the secondary circuit, and a signal included in the local circuit.
2. In a signaling system, electrically connected stations, track rails, vehicles traveling there-over, a source of current independent of the vehicles included in a circuit, a secondary circuit including a source of current, means carried by the vehicle for controlling the first circuit, signals operated at both stations upon completion of said first circuit, means included in the first circuit for controlling the second circuit to partially complete the same, means carried by the vehicle to fully complete said second circuit, and a

continuously ringing bell circuit controlled by the second circuit, said bell circuit being carried by the cab.

3. In a signaling system, electrically connected stations, track rails, vehicles running there-over, a pair of automatic switches at separate stations along the line, a primary circuit for each switch, a secondary circuit for each switch, both including a separate source of current, means in the primary circuit at both stations to partially complete the secondary circuits at both stations simultaneously, means to initially close the primary circuit, said means carried by the vehicles, signals operated at both stations upon completion of said first circuit, contact strips included in the secondary circuits, brushes carried by the vehicle and included in circuit with a relay to engage the contact strips to fully complete the secondary circuit, a continuously ringing alarm circuit carried by the train and controlled by said relay.

In testimony whereof we have hereunto set our hands in presence of two subscribing witnesses.
